UNITED STATES PATENT OFFICE.

HARRY R. WOODROW, OF NEW YORK, N. Y., ASSIGNEE TO THOMAS E. MURRAY, OF NEW YORK, N. Y.

METAL VEHICLE-WHEEL.

1,269,992.

Specification of Letters Patent. Patented June 18, 1918.

Application filed October 19, 1917. Serial No. 197,382.

To all whom it may concern:

Be it known that I, HARRY R. Woodrow, a citizen of the United States, residing at New York, in the county of New York and State of New York, have invented a certain new and useful Improvement in Metal Vehicle-Wheels, of which the following is a specification.

The invention is a metal vehicle wheel, in which spokes are provided with frusto-wedge shaped enlargements at their inner ends, which enlargements are juxtaposed and welded together to form the wheel nave, and wherein annular flange plates are welded to the opposite faces of said nave; and also a method of making said wheel, whereby the said flange plates are electrically welded to the nave, and the spokes electrically welded together at their juxtaposed faces, by a single operation.

In the accompanying drawings—

Figure 1 is a portion of the nave and spokes of my wheel shown in perspective. Fig. 2 is a vertical section of the wheel (rim omitted) placed horizontally between the electrodes, also shown in section, and Fig. 3 is a section on the line 3, 3 of Fig. 1.

Similar letters of reference indicate like parts.

30 The wheel comprises a plurality of preferably tubular metal spokes A, having frusto-wedge shaped enlargements B at their inner ends, which enlargements are placed in juxtaposition to form the wheel nave. C and

35 D are annular flange plates which are to be electrically welded on opposite faces of said nave. On the inner face of each plate C, D are elongated projections E, preferably formed by making struck up indentations disposed radially on said plate, and so placed as to come directly over the radial joints between the spoke enlargements B.

40 I may provide a plurality of projections, due to such indentations, over each joint. For example, the indentations F, F', as shown in Fig. 1, are placed to lie directly over the joint at G, while the indentations H, H' are similarly placed with respect to the joint at I.

50 The wheel is assembled and welded in the

following manner: J is an annular electrode resting on a bed K of insulating material. In the upper surface of said electrode is a recess which receives the flange plate D. The nave formed by the juxtaposed spokes 55 is placed upon flange plate D, and above said nave is placed the flange plate C. The upper electrode L has an annular groove which receives the plate C, and a central downwardly projecting portion M which 60 enters the opening in the nave.

Welding current being established between the electrodes, the upper electrode L, by any suitable means, is forced downwardly, thus causing the flange plates C, D 65 to become welded against the opposite faces of the nave, and at the same time obliterating the projections E on the inner side of said flange plates. The melted metal from said projections E is, by the pressure, forced 70 into the joints between the juxtaposed faces of the wedge-shaped enlargements B of said spokes, and serves on cooling to bind the juxtaposed spoke faces together. In this way, by simply compressing the assembled 75 parts between the electrodes, and establishing the heating current, as described, I am enabled to unite the spokes at their juxtaposed faces, and simultaneously to unite the flange plates to the nave faces; thus accomplishing the desired end in a single operation, and effecting an exceedingly strong 80 union of the parts.

I claim:

1. The method of electrically welding together the spokes and flange plates of a metal vehicle wheel, which consists, first, in juxtaposing the inner frusto-wedge shaped ends of the spokes to form a nave, second, placing against each face of said nave an 85 annular flange plate having radially disposed elongated projections on its inner side, to cause said projections to lie over the joints of said nave, and third, placing said nave and flange plates between electrodes and 90 subjecting said nave and plates to pressure and a welding current, whereby simultaneously the said flanges are welded to said nave faces, and the juxtaposed faces of said spokes are welded together by fused metal 100

from said flange plate projections entering between said spoke faces.

2. A metal vehicle wheel, comprising spokes having frusto-wedge shaped inner ends placed in juxtaposition to form a nave, and flange plates disposed on opposite sides of said nave and electrically welded thereto; the said spokes being united by metal ex-

truded from said flange plates and entering the joints of said nave.

In testimony whereof I have affixed my signature in presence of two witnesses.

HARRY R. WOODROW.

Witnesses:

GERTRUDE T. PORTER,
MAY T. McGARRY.
